BRUSH BAG HOLDER

Joseph Albin, New York, N. Y.

Application November 27, 1940, Serial No. 367,325

3 Claims. (Cl. 206—15.1)

This invention relates to a bag or holder for paint brushes. It lends itself as a protective wrapper in the course of shipment. Its construction renders it of particular service between painting intervals, and as a protective device for the bristles when the brush has been stored away for a future paint job.

Among the several objects of my invention is the provision of a flat pliable bag which is adjustably secured to the head or ferrule portion of the brush so as to obtain structural support from the sides of the bag as they are positioned about the bristles: thus keeping the weight of the brush off the bristles as well as affording mechanical protection of the bristles when the brush is left resting in positions other than upright.

A further object is to provide a bag or holder with an improved mouth edge, attaining by means of it a practically airtight closure of the bag above the bristles by a simple manipulation of the fastening means. An equal degree of closure for brushes having the same width but varying considerably in thickness can also be attained.

A further object is to provide a bag or holder with a non-porous liner or to construct the bag of a pliable material such as paper which has been coated or impregnated with a chemical substance, rendering the bag moisture-proof as well as resistant to the bleeding through to the surface of turpentine or oils that have been left on the brush.

Provision is also contemplated in this invention whereby the bag or holder may be removably attached to a paint can having a wire handle by the addition of no other parts than those already integral. The brush can be conveniently slipped into such a receptacle when it is desired to temporarily discontinue a certain painting application.

A preferred embodiment of my invention as shown in the drawing represents a form of low-cost construction from the angle of those versed in the art of paper bag manufacture.

Fig. 1 is a perspective view of the bag or holder in a generally flat shape preparatory to use.

Fig. 2 is a front view, exhibits the bag or holder fastened around the brush head.

Fig. 3 is a side view of the same.

Fig. 4 is a sectional view along line 4—4 of Fig. 2.

Fig. 5 shows in perspective the bag or holder attached to a paint can.

Referring to the drawing, the body 1 of the bag or holder consists of a single rectangular sheet of paper folded centrally and adhesively

fastened together at the side edges 4—4, forming a pocket. It may also be constructed as a conventional satchel bottom bag with plain folds or tuck-ins at the sides, in either case the bag is a sleeve with a single seam and closed at one end. The mouth of the bag will be sufficiently ample to permit the brush to be easily deposited therein, if allowance is made for the vertical side portions as areas 3—3 to act as flaps or flanges. In Fig. 2 these side portions are drawn towards each other and pressed against the front portion or panel 12; the edges 4—4 are positioned somewhat parallel to each other and spaced apart so as not to interfere with the twisting of the string 5 around the button or buttons 6—6.

The effectiveness of such an economical and simply applied fastening means as string and button in connection with a bag as described is greatly increased by the provision of strips 7—7 affixed to opposite portions of mouth edges. The strips may be made of tin or Celluloid, a thickness of about .015 inch imparts sufficient rigidity over the portions of the mouth edges they extend. The strips may be attached by stapling means or adhesively as shown in the drawing. In the latter method, a piece of paper is utilized; the paper is wrapped around the strip, and a lap 8 is allowed for extra adhesion area. Length of strip should not be greater than side of ferrule to which it conforms.

The strips help achieve an evenly contiguous fitting of the mouth edges about the brush head or ferrule 9, Figs. 2, 3, and 4. Thus, gaps are eliminated between those sections of the mouth edges rendered rigid by the strips and the flat faces of the ferrule. As the side portions 3—3 are brought together by action of string and button, a tight conforming closure of mouth edge sections 10—10 around the sides of the ferrule 9—9, Fig. 4, is also effected. For sake of clearness in representation this latter closure is incompletely shown in Fig. 4. In the same bag designed to accommodate an approximately given width of brush, practically airtight closures can be attained for brushes differing in thickness. As an additional advantage, the strips serve to locate the brush in the central portion of the bag as soon as brush is deposited therein; a tight fitting around any suitable level of the ferrule can be made in a very short space of time.

For fabricating these bags, a tough, compacted, non-laminated kraft paper such as used for sandpaper, is preferred. This kraft paper is easily creasible, possesses an amount of resiliency and is of fairly low porosity. The paper can be ren-

dered resistant to the action of turpentine bleeding through to the surface by having the paper coated or impregnated with a suitable chemical, such as synthetic resin. The bag may also be made with a liner of extremely low porosity and sufficiently resistant to the action of turpentine and paint vehicles not to develop cracks or holes after an amount of repeated creasing. Liners made of Pliofilm or certain of the vegetable parchments are satisfactory for this purpose.

When a bag or holder as described in the foregoing is applied to a brush, certain structural elements are present which will protect the bristles; that is, will help maintain them in a parallel alignment. Fastening means are applied at any convenient level of the ferrule which will keep the bristles of the inserted brush elevated above the bottom of the bag 11. The longitudinal side portions on either side of the brush are brought around to the front and creased, as shown at 9-9, Fig. 4, forming flaps or flanges 3-3. The string 5, may be twisted around both buttons 6-6; or, one button 6 may be used and the string 5 is carried around the entire bag, as shown in side view, Fig. 3. A pull needs to be exerted on the string as the flanges are brought towards each other, by the action of the string as it is drawn around the buttons. In this way the ferrule engaging edges and other sections of the mouth edge enclose the brush tightly all around and thus prevent the brush from sliding within the bag. Referring to Fig. 2, the flanges cooperate with the front panel 12 of the bag to constitute two longitudinally angular structural elements. After the bag is fastened to the ferrule, the flanges serve to protect the alignment of the bristles from the force of superimposed objects when the brush is left in a flatwise position. The brush may be left resting edgewise, in which case the flanges provide structural protection in cooperation with the fastening means: movement of points 11-11 at bottom of bag towards each other due to an external weight is opposed by a leverage force exerted by fastening means applied at upper part of flanges.

Referring to the drawing, Fig. 5, the bag is shown removably attached to a paint can or a pail of the type having a wire handle pivoted on hinges located at the sides. When applying the bag to a can, the side portions are folded to form flanges, edges 4-4 of these edges are towards the can. The string 5 of substantial length permanently fastened to button 6a is carried around the can over the handle hinges 12-12 and then twisted on button 6. As the bag is supported by and allowed to hang somewhat loosely from the handle hinges, the size of the mouth opening may be additionally increased to conveniently receive a brush by pressure of the finger on edge 7a. The location of the buttons in the upper corners of both flanges causes the body of the bag to remain in a nearly vertical position, with the flanges

resting against the sides of the can, and the mouth horizontal. The can may be lifted by means of the handle but the brush will not lean away from the can in any direction nor will paint drip out of the bag.

While the present preferred embodiment of the invention has been illustrated and described in some detail, it should be understood that the invention is not to be limited to the precise details here set forth, but may be carried out in other ways, as falling within the scope of the claims.

I claim as my invention:

1. A brush bag holder, comprising an open mouth pocket, a rigid reinforcing strip secured to opposite sides thereof adjacent the upper edge of the open end, string and button attached to opposite ends of said pocket adjacent the upper edge and substantially in the same plane as reinforcement means, said pocket having a width much greater than the width of the brush to be held therein and the length of the rigid reinforcing strips being less than the width of the brush to be supported therein, said string and button means employed to draw the opposite ends of said pocket towards one another about said brush and tightly secure the upper edge of pocket to the brush, said reinforcing member tending to tightly seal the upper edge of pocket to ferrule when in operating position, said pocket being impervious to oil and adapted to maintain linseed oil therein.
2. A brush bag holder, comprising an open mouth pocket, a rigid reinforcing strip secured to opposite sides thereof adjacent the upper edge of the open end, string and button attached to opposite ends of said pocket adjacent the upper edge and substantially in the same plane as reinforcement means, said pocket having a width much greater than the width of the brush to be held therein and the length of the rigid reinforcing strips being less than the width of the brush to be supported therein, said string being of sufficient length to go around a paint bucket and clamp brush to bucket, said pocket being impervious to oil and adapted to maintain linseed oil therein.
3. A brush bag holder, comprising an open mouth pocket, a rigid reinforcing strip secured to opposite sides thereof adjacent the upper edge of the open end, string and fastening means attached to opposite ends of said pocket adjacent the upper edge and substantially in the same plane as reinforcement means, said pocket having a width much greater than the width of the brush to be held therein, and the length of the rigid reinforcing strips being much less than the width of the pocket so as to permit the ends of said pocket to fold, forming flanges, said string being of sufficient length to go around a paint bucket and clamp brush to bucket, said pocket being impervious to oil and adapted to maintain linseed oil therein.

JOSEPH ALBIN.
